UNITED STATES PATENT OFFICE.

JOHN P. KIRK, JR., OF AUSTIN, TEXAS.

DESIGN FOR A MEDAL.

SPECIFICATION forming part of Design No. 18,204, dated March 27, 1888.

Application filed December 15, 1887. Serial No. 258,031. Term of patent 3½ years.

To all whom it may concern:

Be it known that I, JOHN P. KIRK, Jr., a citizen of the United States, residing at Austin, in the county of Travis and State of Texas, have invented and produced a new and original Design for Medals, of which the following is a specification, reference being had to the accompanying drawings, forming part thereof.

In the drawings illustrating my design for a medal, Figure 1 is an elevation showing the obverse face. Fig. 2 is an elevation showing the reverse face.

The medal is of circular-disk form and provided with a loop on the edge of the same. On the obverse side of the medal in Fig. 1 I form two annular beads parallel to each other, and within the one of smaller diameter I form or outline with a bead or molding a five-pointed star. In the area inclosed by the said star outline I show a perspective view of the Texas State capitol, having a foreground and a sky-lining background relief. Within the points of the star, outside the view of the building aforesaid, I leave a space for letters. In the space outside of the star I form a scroll for mottoes or other inscriptions, and I reserve the space outside of the star for some pertinent inscription. In the annular space between the circular beads on the obverse side, at intervals, I form stars, as shown, and between these is a space for an inscription. On either side within said annular space, at the bottom, I form a spray of flower-blossoms.

The reverse side of the medal is provided

with annular beads like those of the obverse side, and within the space inclosed by these beads I arrange a garland of leaves and berries tied in the middle with a ribbon bow. I form a scroll across the diameter of the medal on this side, within which may be placed suitable inscription. The segmental spaces formed above and below the scroll across the diameter are provided for inscriptions.

Having thus described my design, what I claim, and desire to have protected by Letters Patent, is—

1. The design for a medal, as shown and described, having on its obverse side two parallel annular beads inclosing two strings of blossoms and four stars, a five-pointed star the points of which touch the inner of said beads, the picture of the Texas State capitol, with foreground and sky background inclosed within the outlines of the star centrally, and a scroll at the bottom of the space inclosed by the inner annular bead and the outline of the said star, as set forth.

2. The design for a medal, as shown and described, having on its reverse side two annular beads, with an inclosed annular space ornamented with a garland of leaves and berries tied by a ribbon, and a space within the inner of said beads divided by a scroll for data, as set forth.
